UNITED STATES PATENT OFFICE.

ERNEST FOURNIER AND THÉODULE TESTU, OF NICE, FRANCE.

BLOCK-SIGNALING APPARATUS FOR RAILROADS.

1,380,890.

Specification of Letters Patent. Patented June 7, 1921.

Application filed December 26, 1916. Serial No. 138,983.

To all whom it may concern:

Be it known that we, ERNEST FOURNIER and THÉODULE TESTU, both citizens of the French Republic, and both residing at Villa 5 Mignon, Avenue Buenos-Ayres, in Nice, Alpes Maritimes, France, have invented certain new and useful Improvements in and Relating to Block-Signaling Apparatus for Railroads, of which the following is a specification.

This invention has for its object to provide an improved block signal indicator which will assure the stoppage of trains in front of a signal at danger. This stoppage 15 is effected by the operation of brakes due to the action of a movable ramp mounted on a longitudinal member carried by the axle boxes of a train vehicle; this action of the ramp being effected by means of a tappet 20 which projects beyond the rail and is placed into such projecting position by the operation of the corresponding signal. At the same time, the apparatus notifies automatically the train driver of the state of the 25 signal which he has just passed, and it also records the fact that this signal is at danger, and it further records the fact whether the driver has seen it in this position before passing it.

30 In the accompanying drawings which illustrate an embodiment of this invention:

Figure 1 is a general side elevation of the apparatus set up on the track and of the truck of the tender of a locomotive comprising the moving parts.

Fig. 2 is an underside view of the said truck.

Fig. 3 is a diagrammatic view showing the apparatus in operation.

40 Fig. 4 is a plan showing a detail of the sliding member A, and it illustrates the working of the signal.

A is the sliding member for operating the rod B of the disk C; it is provided with a 45 chain or other means D for operating the same from a distance and it is engaged in the known manner by a chain E which is connected at its other end to a lever F fitted with a counterweight G fixed on an axle H adjacent to the track. Upon this axle H there is keyed a lever I provided with a roller J which actuates through the medium

of a slotted crank K a tappet L mounted on the same axle as itself.

Upon the two axle boxes M and N (corresponding to the track rail O) of the tender P or other vehicle of the train, there is fixed a longitudinal member Q upon which there is pivoted at R a bell cranked lever S one arm of which forms a ramp T which is guided at U by a rod V and forms at its end a counter-ramp W. This lever S is pivoted at its upper end to a tension rod X provided with a returning spring Y and carrying a finger Z in the path of which there is arranged the lever 1 of a cock 2 placed on the train brake pipe 3 of usual construction. The operation of this cock is adapted to cause the application of the brakes and in Figs. 1, 2 and 3, I show by way of example 70 the cock applied to a system operated upon the vacuum principle, the operation of the cock being such as to place the train pipe into communication with the atmosphere via a steam injector.

75 The brake apparatus comprises as usual sets of brake shoes 4 actuated by means of rodding 5 provided with a piston 6 working in a cylinder 7. A control (not shown) is provided to enable the driver to shut the 80 cock 2 without getting down from his engine.

When the track is free, that is to say, when the disk C is parallel to the track, as shown in Fig. 1, the chain E maintains the 85 lever F with its counterweight in a position in which the lever I is depressed, so that the tappet L lies flat alongside the rail, and the ramp T of each engine can pass freely over the said tappet.

90 When the disk C is operated to close the line, that is to say, when it is set at danger by means of the transmission D, the chain E will release the lever F which by the action of the counterweight G, assumes the 95 position shown in Fig. 3, wherein it causes the tappet L to rise and project above the rail.

100 When a train enters a section of the track which is thus closed, the ramp T is raised by the tappet L and assumes the position shown in Fig. 3, operating the rod X by means of the lever S, and thereby opening the cock 2. The train brake pipe thus

placed in communication with the atmosphere via the steam injector will be exhausted of air and thereby cause all the brakes of the train to come into action and stop the train as is the case in the working of an alarm signal. Air will also be exhausted from the cylinder 9 and the piston 10 in said cylinder will consequently be actuated. This piston carries at its end a stylus 11 which is in permanent contact (that is to say, marks a continuous line) with the recording drum 12. This stylus will draw a diagram upon the sheet of the recorder each time the train meets a signal set at danger. Further, a second stylus 13 is also in permanent contact with the sheet of the recorder, but its marking can be interrupted by bearing upon its end. Consequently, when the driver perceives a signal at danger before coming up to it, it will be sufficient for him to press upon the end of this stylus 13 to produce a break in the line marked on the recorder and thus record the fact that he has seen the signal at danger before passing it. The agreement of the diagram marked by the stylus 11 and of the break in the line marked by the stylus 13 will furnish an efficient and certain check upon the attention which drivers should give to the position of signals.

As soon as the ramp T has passed its culminating point, a counter-ramp W inclined in the opposite direction, guides the descent of the ramp under the pressure of the returning spring Y, and thereby avoids the occurrence of a sudden shock at the moment of its return into the normal position and allows of the train traveling in the opposite direction on the same track.

The actuating mechanism of the cock 2 is located on a longitudinal member Q which is fixed to the axle boxes of the vehicle, and is therefore located always at an unvarying distance from the track rail. The result of such an arrangement is that this control assures the working of the apparatus irrespectively of the load of that portion of the train to which the apparatus is applied, and the speed of the train. The arrangement provided for the purpose of maintaining the ramp at an unvarying distance from the track rail is shown by way of example only. The ends of the axles for instance may also serve for fixing the center of rotation of the ramp.

The arrangement of the hereinbefore described devices which are actuated automatically by the operation of a disk or other signal, renders impossible any accident upon railroads provided with the improved block apparatus, and it avoids also a collision between trains on converging tracks whose signals are interconnected.

The improved apparatus may be applied to trains fitted with brakes operated by com-

pressed air by suitably modifying the arrangement of the cock 2.

In the case of trains that are not fitted with vacuum or air brakes, the improved apparatus may be operated by steam, and it can also operate a whistle or any other audible or optical signal, while at the same time operating the recorder.

The invention is applicable to railroads and tramways of all kinds. It can be employed also for protecting level crossings, working operations on the line, etc.

What we claim is:—

1. In a railway safety appliance, the combination with the train pipe of a valve, the operation of which automatically causes the operation of the brakes, a bell-crank lever adapted to operate such valve and fulcrumed on a member supported at an unvarying distance above the track rail, one arm of such bell-crank lever being operatively connected to said valve and the other arm being in the form of a ramp having an extension in the form of a counter ramp, such ramp being adapted to be actuated by a movable tappet located by the side of the track, a cylinder in communication with the train pipe, a piston mounted in said cylinder and carrying a marking device, such piston being actuated on the operation of the aforesaid valve, and a recording drum co-operating with said marking device.

2. In a railway safety appliance, the combination with the train pipe of a valve, the operation of which automatically causes the operation of the brakes, a bell-crank lever adapted to operate such valve and fulcrumed on a member supported above the track rail, one arm of such bell-crank lever being operatively connected to said valve and the other arm being in the form of a ramp having an extension in the form of a counter ramp, such ramp being adapted to be actuated by a movable tappet located by the side of the track, a cylinder in communication with the train pipe, a piston mounted in said cylinder and carrying a marking device, such piston being actuated on the operation of the aforesaid valve, a recording drum co-operating with said marking device and a manually operated marking device also co-operating with said drum and designed to be disengaged from the drum during the actuation of the valve.

3. In a railway safety appliance, the combination with the train pipe of a valve, the operation of which automatically causes the operation of the brakes, and a bell-crank lever adapted to operate such valve and fulcrumed on a member supported by the axle boxes of the car and thus supported at a point located at an unvarying distance above the track rail, one arm of such bell-crank lever being pivotally connected to a rod which is operatively connected to said valve, the other

arm of the said bell-crank lever being in the form of a ramp having an extension in the form of a counter ramp, a rod being fixed to the said ramp and slidably engaging with the member supported by the axle boxes of the car, such ramp being adapted to be actuated by a movable tappet located by the side of the track.

In testimony whereof we have signed our names to this specification in the presence of 10 two subscribing witnesses.

ERNEST FOURNIER.
